CLAIM

The ornamental design for a weaning cap for nursing bottles, as shown and described.

DESCRIPTION

FIG. 1 is a front elevational view of a weaning cap for nursing bottles showing my new design, the rear being identical;

FIG. 2 is a top plan view thereof;

FIG. 3 is a bottom plan view thereof;

FIG. 4 is a cross sectional view taken on line 4—4 of FIG. 1;

FIG. 5 is a perspective view thereof shown in the position of use, the broken line showing of a nurser being for illustrative purposes only and forming no part of the claimed design; and,

FIG. 6 is a top plan view of an alternate embodiment of the design shown in FIG. 1.

FIG. 2
